(57) **CLAIM**

The ornamental design for a toy projectile launching assembly, as shown and described.

DESCRIPTION

FIG. 1 is a perspective view of a first embodiment of the toy projectile launching assembly.

FIG. 2 is a front elevational view of the toy projectile launching assembly.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a perspective view of a second embodiment of the toy projectile launching assembly shown with a forward projectile sleeve removed.

FIG. 9 is a front elevational view of the toy projectile launching assembly.

FIG. 10 is a rear elevational view thereof.

FIG. 11 is a left side elevational view thereof.

FIG. 12 is a right side elevational view thereof.

FIG. 13 is a top plan view thereof; and,

FIG. 14 is a bottom plan view thereof.

The broken lines shown in the drawings represent portions of the article that form no part of the claimed design.

1 Claim, 10 Drawing Sheets
